UNITED STATES PATENT OFFICE.

LEWIS HALLOCK NASH, OF BROOKLYN, ASSIGNOR TO THE NATIONAL METER COMPANY, OF NEW YORK, N. Y.

GAS-ENGINE.

SPECIFICATION forming part of Letters Patent No. 312,497, dated February 17, 1885.

Application filed January 22, 1884. (No model.)

To all whom it may concern:

Be it known that I, LEWIS HALLOCK NASH, a citizen of the United States, residing at Brooklyn, in the county of Kings and State 5 of New York, have invented new and useful Improvements in Gas-Engines, of which the following is a specification.

In United States Letters Patent granted to me under date of December 4, 1883, No. 289,693, I have described and claimed certain improvements in gas-engines in which the gaseous charge is formed by air compressed within a chamber of the engine-cylinder and a portion passed through a body of hydrocarbon, from whence it passes to the combustion-chamber in carbureted condition with pure air from said storage chamber to complete the charge. It has also been proposed to operate explosive-vapor engines by forcing air under pressure from an independent compressor into a vessel containing hydrocarbon, from which vessel both the liquid and partially-carbureted air pass into the combustion-chamber, so as to fill with this mixture of air and liquid the space swept through by the piston, the hydrocarbon being sprayed into the cylinder by the force of the air-pressure upon its surface in the vessel, and the air mixing with it only on reaching the cylinder. In my said patent the engine-cylinder forms a compression-pump for the air, which tends to unduly increase the heat of the working parts of the engine, while it is impossible to control by air-pressure the injection of the hydrocarbon into the engine from the air-tight vessel, so as to give a succession of uniform charges, because a very minute spray of hydrocarbon will produce a large amount of fuel-vapor. My improvement is directed to a remedy for this difficulty, to certain improvements in preventing the heat of the combustion-chamber from being communicated to the power-cylinder, the piston, and its working parts, and to certain improvements in the lighter for igniting the charge.

My invention further embraces matters of construction and of combinations, which will be subject of specific claims.

Referring to the accompanying drawings,

Figure 1 represents a vertical longitudinal section of a gas-engine embracing my invention for maintaining the temperature of the gases in the power-cylinder; Fig. 2, a horizontal longitudinal section of the engine, showing the independent air-compressor, the valve system, and the independent lighter; Fig. 3, a cross-section of the engine, taken on the line *z z* of Fig. 2, showing the means for supplying the engine with fuel; Fig. 4, a sectional detail of the exhaust-valve. Figs. 5, 6, 7, 8, 60 and 9 show enlarged views of the independent lighter, illustrating its operation, Fig. 6 in these views being a cross-section on the line *x x* of Fig. 5, and Fig. 7 a cross-section on the line *y y* of Fig. 5; and Fig. 10 shows a modified form of the means for maintaining the temperature of the gases in the cylinder.

Having thus briefly stated the several matters of my invention and described the drawings which illustrate one form of engine adapted for carrying it into effect, I will now more particularly describe the construction and operation of my engine preparatory to a specific designation of the things and combinations of parts claimed as my invention.

The engine is of the single-acting type, and the cylinder *A* is open at the forward end, which is surrounded by a water-space, *B*, formed in the casting to admit cold water for the purpose of cooling the cylinder, as in the ordinary water-jacket. The combustion-chamber *C*, or power end of the cylinder, is enlarged internally in its diameter to form a recess to receive a lining adapted to form a non-conductor for heat, extending from the head a distance equal to the stroke of the piston, more or less. The cylinder-head *D* is in like manner recessed internally to receive a non-conductor of heat, which joins and laps the end of the cylinder non-conductor, so that the walls of the combustion-chamber are lined with a heat non-conductor. The cylinder non-conducting lining stands in the recess slightly back of the bore of the cylinder, so that piston *E* will work within the bore free of the lining. The piston has the usual packing, and has a suitable bearing-surface within the cylinder. It has a cylindrical hood or shield, *F*, made

hollow and secured to the back of the piston by any suitable means, so as to make it practically an integral part of the piston. The hood or shield does not form a joint-bearing 5 with the cylinder, nor does it touch the cylinder-lining, and it is of sufficient length to have its chamber deep enough to prevent the heat from the combustion-chamber being quickly communicated to the piston, and to 10 bring its rear end in close proximity to the head-lining of the cylinder when the piston has reached the limit of its back-stroke. The rear end of the piston-shield is recessed to receive a non-conducting lining similar to the 15 walls of the combustion-chamber, so that the walls of the said chamber will be formed of non-conducting lining.

The object of forming the combustion-chamber with non-conducting walls is to entirely 20 isolate the hot gases from any cooling influence, so that in expanding in developing power the total heat of the gases shall be converted into useful work.

It is necessary in the working of a gas- 25 engine that its wearing parts must be in a comparatively cool condition, while the conditions of greater efficiency require that the gases shall be kept at the highest possible temperature.

30 It has been the practice heretofore in gas-engines to secure a low degree of temperature of the working parts by using a cooling-water jacket for the cylinder. This necessarily cooled the combustion-chamber, so that the 35 intensely-hot gases, being in a comparatively cold chamber, rapidly gave up their heat to the walls of the combustion-chamber, thereby greatly reducing their elastic force, and consequently the power and efficiency of the engine were correspondingly reduced, the heat 40 thus imparted to the walls of the combustion-chamber being a dead loss.

The combustion-chamber being inclosed by a non-conducting material, the inner surface 45 of said chamber may have an intensely-hot temperature, which, however, will be less than that of the gases at the instant of ignition. At this instant the inner surface of the non-conducting lining will receive some 50 heat from the contact of the hot gases; but as the gases expand in driving the piston their temperature will be rapidly reduced until they reach a temperature lower than that of the inner surface of the combustion-chamber. The excess of heat in the walls of the 55 combustion-chamber will now be imparted to the expanding gases, and thereby increase their elastic force during the latter portion of the stroke of the piston, and correspondingly increase the power developed by the engine. While, therefore, obtaining the advantage of 60 working with an intensely-hot combustion-chamber, I at the same time obtain the advantage of working the piston in a comparatively cool cylinder.

I may maintain the working part of the en-

gine in a cool condition by means of other than the water-jacket—for instance, by enveloping the cylinder by the working-fluid, as set forth in my patent of November 27, 70 1883, No. 289,019.

The non-conducting lining is preferably used in the manner represented in the drawings—that is to say, it may consist of one or more thin metal plates or sheets, *a*, separated 75 by intervening spaces from each other and from the cylinder-walls.

The plates or sheets I prefer to form of open cylinders or rings fitted one within the other in the recess in the walls of the cylinder, as 80 stated; or they may be formed of a coil held in place, with the coils separated by any suitable means. The plates for the head of the cylinder and piston-shield are necessarily flat disks held in place by any suitable means; but 85 I prefer that the head-plates shall lap with those of the cylinder-walls. While I prefer to form such lining in the manner described, yet it may be formed by any suitable non-conducting material, with or without a metallic facing, 90 as shown in Fig. 10. I may also fill the chamber *F*² of the piston-shield *F* with any suitable non-conducting substance.

The piston is operated by any suitable crank-connections and the power transmitted in 95 the usual manner. I use an air-compressor, *A'*, independent of the power-cylinder, as shown in Fig. 2, consisting, in the example shown, of a cylinder open at one end, having a trunk-piston surrounded with a water-jacket, which may form a continuation of the water-jacket of the power-cylinder, as shown. These two cylinders may also be separate or cast integral. The air is admitted to the compression-chamber *b* through a check-valve, *c*, in the head of said chamber, arranged to open inward in a well-known manner. Water is injected into the compression-chamber *b* through the pipe *d*, either before or during the compression of the air, by means 100 of a suitable pump (not shown) adapted to be worked by the engine. The air-compression chamber communicates with the combustion-chamber *C* of the power-cylinder by a chest, *G*, extending from the end of the compressor 105 and opening into the cylinder-port *e* of the engine, as shown in Figs. 2 and 3, such communication being controlled by a check-valve, *f*, and the main inlet-valve *g* of the engine arranged within said chest back of the valve 110 *f*. The exhaust-valve *h* discharges from the same port, *e*, into the exhaust-pipe *i*. These valves are operated each by an eccentric, *j*, operated by the shaft *H*, which is driven by suitable gearing, *I*, by the crank-shaft *J*, the 115 eccentric-rods *k* having a loose connection with their valve-stems, as shown in Fig. 4, the object of which will be hereinafter stated. The object of injecting the water into the air-compression chamber is to prevent the air from 120 being unduly heated while being compressed. A portion of the compressed air is admitted 125 130

into the combustion-chamber by the means stated, while another portion is conveyed by the pipe *l* into an air-tight vessel, *K*, containing a volatile liquid fuel placed in any suitable relation to or distance from the engine, the conducting-pipe preferably entering the bottom of said vessel. The air admitted into this vessel passes through the liquid fuel therein, which may be gasoline or other volatile liquid, and absorbs sufficient of the oil to form the gaseous fuel, which collects in the chamber of the vessel above the surface of the liquid fuel, it being understood that this chamber is never to be completely filled with the liquid fuel. The passage *e* of the engine communicates with the top of this air-tight vessel *K* by means of a pipe, *m*, as shown in Fig. 3, and such communication is controlled by a suitable governor, *n*, to admit the gaseous fuel from the air-tight chamber under pressure into the chest *G*, whence it passes into the cylinder through the port *e*, being admitted by a valve, *o*, operated by the engine. (Shown in Fig. 3.) The pipe *m* is provided with a check-valve, *r*, to prevent back-pressure of the gas from the cylinder, while the pipe *l* is provided with a similar check-valve, *r'*, to prevent the backflow of the liquid from the vessel *K*, which might occur from the force of the suction of the air-compressor. The gas-supply is controlled by the valve *o* in the bottom of the chest *G*, adapted to cross the entrance-port of the pipe *m*, and operated by a rod, *o'*, connected by a rocker-arm, *o''*, with the eccentric-rod *k*, so that the reciprocating movement of the latter is communicated to the valve *o*, to control the admission of the gas, as stated.

I use a means for lighting the charge independent of the valve system of the engine. It consists of a separate lighting device connected with the combustion-chamber by a pipe or passage, *s*, opening into a cylindrical case, *t*, adapted to receive a cylindrical lighter-valve, *u*, operated by an eccentric, *j*, on the valve-shaft *H* through the eccentric-rod. The case *t* of the lighter-valve *u* is surrounded by a water-jacket, *t'*, to prevent the device from becoming overheated, and the supply of water may be by any suitable means. The case of the lighter-valve has two ports, *v* *w*—one, *v*, to admit the flame into the chamber *v'* of the valve from an exterior permanent burner, *x*, placed so that the flame from said burner shall be communicated to the gas within the valve-chamber, and the other, *w*, communicates with the pipe *s* and with the valve-chamber in the operation of the valve, as shown in Fig. 9. The valve-chamber *v'* is placed crosswise of the valve, and opens at opposite sides of its circumference, so as to open and close the ports *v* *w* at the proper time. The ignition in the valve-chamber *v'* is made, when the port *w* is closed, by means of a jet, *v''*, from a passage, *v''*, in the case opening into the pipe *s* and into the valve-chamber. Instead of making this jet-

passage in the side of the case, as shown, it may be made in the lighter-valve, as shown by dotted lines in Fig. 5.

In the operation of the lighter, as described, it is advantageous to place the pipe *s*, connecting the lighter-valve with the combustion-chamber, near to the point where the fuel entering through the pipe *m* enters the engine, so that the combustible mixture passing into the pipe *s*, in supplying the lighter, shall be heavily charged with the fuel, and thus be capable of quickly receiving the flame from the lighter and communicating it to the charge in the combustion-chamber. For this purpose I have shown the pipe *e'*, Fig. 2, conveying the said gaseous fuel, as extending a short distance within the engine-port *e*, and communicating with the passage *e''*, placed beneath the passage *e*, as shown in Fig. 3 and in dotted lines in Fig. 2, which passage *e''* supplies the fuel to the engine. After the charge is admitted to the combustion-chamber of the engine a portion of it passes through the pipe *s* and the jet-passage *v''*, supplying the jet *v''*, which is lighted by the permanent lighter-flame *x* through the port *v* when the valve is in the position shown in Fig. 5. When the valve has reached the position shown in Fig. 8, the port *v* is closed and the port *w* is just beginning to open, so that the charge from *s* enters through the edge of the port *w* in a jet, *v'*, and is lighted by the jet *v''*, which continues lighted as the valve moves into the position shown in Fig. 9, opening the port *w* wider, so that the flame can be communicated to the gas in the pipe *s*. To maintain a continuous jet at *v'* after the port *v* has been closed, a jet-passage, *v''*, is provided in the case to give a vent for the incoming gases in the valve-chamber. The inlet and outlet valves are operated by the eccentrics *j* in proper order, as stated, and, as shown in Fig. 4, the eccentric-rod *k* of each valve has a loose connection with the valve-stem. This loose connection is formed by an open or recessed end of the eccentric-rod *k* terminating in hook-points *k' k'* and a button, *h'*, on the end of the valve-stem, adapted to move within the said recess or opening, and forms a shoulder between which and the said hook-points a coil-spring, *h''*, is placed, and acts to keep it closed when the eccentric-rod is on its back-stroke. This loose joint-connection operates to allow the exhaust-valve to be closed during a portion of the stroke of the eccentric, and it is opened when the eccentric moves so as to bring the button *h'* in contact with the end *k'* of the recess in the eccentric-rod. The inlet-valve *g* is provided with a similar loose joint-connection, but is opened in the reverse direction by the action of the valve-stem button *h'* against the hook-points. The engine being in motion, the air is admitted through the check-valve *c* and compressed by the back-stroke of the compressor-piston, and during such compression, or during the admission of

the air, a definite quantity of water is injected into the compression-chamber through the pipe d , to absorb the heat developed in the compression of the air. A portion of the 5 compressed air passes through the valve f into the chest G , and is admitted at the proper time into the combustion-chamber by the inlet-valve. Another portion of the compressed air passes from the compression-chamber 10 through the pipe l into the vessel K , where it absorbs a quantity of the liquid fuel, and passes thence through the pipe m into the passage e by the valve o , and mixes with the air passing into the combustion-chamber to complete 15 the charge, which is lighted as stated.

I have shown and described the gas as being supplied by passing a portion of the compressed air through a confined body of liquid fuel; but as this source of the gas may not always be desirable or available I may supply 20 the gas to the engine from any other source, in which case it must be admitted into the air-compression chamber, and for this purpose I have shown a pipe, d^2 , in Fig. 3, provided with a check-valve, d^3 , through which the gas passes into the compression-chamber, so that the gas will in this case be compressed 25 with the air and the water, or with both, and the charge therefrom conducted into the power-cylinder through the engine-valves. In such case the other fuel-supply may be disconnected or not provided.

I have shown the independent lighter as being arranged upon the combustion-chamber, 30 so as to supply the igniting-jets from the charge therein contained; but the lighting of the charge can be effected if the lighter were placed upon any part or passage communicating with the power-cylinder—as, for instance, 40 the passage e .

The admission of the gaseous fuel to the engine is controlled by the governor n , arranged on the supply-pipe m , to regulate the amount supplied to the combustion-chamber 45 from the vessel containing a volatile liquid fuel, and the governor so arranged to operate with the independent air-compressor in an engine operated by gaseous fuel produced from a volatile liquid, the governor being operated by the pulley j^2 on the valve-operating shaft.

I claim—

1. The method substantially herein described of operating an explosive engine, 55 which consists in dividing a charge of air compressed in a chamber independent of the engine, passing a portion of the air into and through a body of hydrocarbon, conducting the carbureted air into the power-cylinder, 60 and completing the combustible charge by admitting the other portion of the compressed air into said cylinder direct from said independent compressor, substantially as described.

65 2. The method herein described of operating an explosive-gas engine, which consists in

dividing a charge of air compressed in a chamber independent of the engine, passing a portion of the air into and through a body of hydrocarbon, conducting the carbureted air 70 into the power-cylinder in quantities regulated by a governor, and completing the combustible charge by admitting the other portion of the compressed air into said cylinder, as described.

3. The combination, with the cylinder of an explosive-vapor engine and an independent air-compressor, of an air-tight vessel for containing hydrocarbon, a pipe, l , connecting said independent compressor with the bottom of said vessel, the pipe m , connecting the top of said vessel with the engine-valves, the supply and exhaust valves $f g h$, and a governor, n , arranged upon the pipe connecting the engine with the top of said vessel, substantially 85 as set forth.

4. The combination, with the power-cylinder of a gas-engine and a water-jacketed air-compression pump, A' , of an air-tight vessel, K , for containing hydrocarbon, the pipes $d d^2$ 90 $m l$, and the valves $f g h$, all constructed and arranged as described.

5. A gas-engine having the walls of its combustion-chamber and the face of the piston lined with a multiple of thin plates separated 95 by air-spaces, as described, for the purpose specified.

6. The combination, with the cylinder of a gas engine, of a non-conducting lining for the walls of the combustion-chamber thereof, composed of thin metal plates separated by air-spaces, so as to insulate the cylinder proper 100 from the direct contact of the heat of the gases.

7. The combination, in a gas engine, of an independent compression-pump having a water-jacket and means for injecting water into its compression-chamber with a power-cylinder having a water-jacket and a non-conducting lining, and a lighter device having a water-jacket, substantially as herein set forth.

8. The combination, with the cylinder of a gas-engine, of an external lighter composed of a shell, t , and a slide-valve, u , both having ports communicating with the air and with the combustion chamber, the shell-port v^3 , for lighting the gas in the valve-port v' when the latter is closed to the combustion-chamber and open to the air, and the shell-port v^5 , for maintaining the lighting-jet when the valve-port v' is closed to the air, and the permanent burner x , substantially as described.

9. The combination, with the cylinder of a gas-engine, of the main inlet and exhaust valves $g h$, having a joint-connection with their eccentric connecting-rods, consisting of the hook-points $k' k'$, the valve-stem having a button, k' , and the spring k^2 , substantially as 130 described, for the purpose specified.

10. The combination, with the cylinder of

a gas-engine, of the pipe e^2 , entering the supply-port e of the cylinder, and a valve-lighter having its igniting-jets supplied independent of the valve system of the engine, substantially as set forth.

11. The combination, with the cylinder of a gas-engine, of a lighter having its igniting-jets supplied independent of the valve system of the engine, consisting of a case, t , having to a suitable connection with the combustion-chamber, the ports v w and passages v^3 v^5 ,

and the valve u , having the chamber v' , a permanent external burner, x , and suitable means for connecting the valve with the shaft H , substantially as described.

In testimony wherof I have hereunto set my hand in presence of two subscribing witnesses.

LEWIS HALLOCK NASH.
